UNITED STATES PATENT OFFICE.

DAVID G. EARL, OF LONG BEACH, CALIFORNIA.

BURGLARPROOF BANK CONSTRUCTION.

Application filed January 4, 1928. Serial No. 244,414.

This invention relates to a burglar proof construction in which the paying teller is not brought into direct contact with the patron and cannot be reached by the patron.

5 An object of my invention is to provide a bank construction in which the teller appears to be immediately in front of the patron, but in reality is not in this position but is securely protected and stands to one side of 10 the window.

Another object is to provide a bank construction in which the transaction between the teller and the patron is carried on in the usual manner, and in which conversation 15 may be freely carried on without exposing the teller.

Still another object is to make the teller's cage or compartment visible from the front of the bank, so that any tampering with the 20 safe or the like can be seen by the watchman.

Other objects, advantages, and features of invention may appear in the accompanying drawings, the subjoined detailed descriptions, and the appended claims.

25 In the drawing—

Fig. 1, is a transverse sectional view of my bank construction.

Fig. 2, is a front elevation of the same.

Fig. 3, is a transverse sectional view of 30 the drawer arrangement.

Referring more particularly to the drawing, the numeral 1, indicates a wall preferably formed of steel or other suitable bullet proof material and preferably extends 35 across the entire bank room completely enclosing or shutting apart the teller safe, and other places in which money is kept.

A window 2, is provided in the wall 1, which is of the usual construction employed 40 in banks for the purpose of paying and receiving money. Extending rearwardly from the window 2, and on both sides thereof, I provide walls 3, 4, which walls are also bullet proof material and extending at an angle 45 and rearwardly from the end of the wall 3, I provide a mirror 5.

The teller's desk 6, extends to one side and back of the wall 4, and upon this desk the teller performs his duties and while standing 50 at this desk he is clearly visible to the patron standing in front of the window 2 in the mirror 5, that is, he appears to stand immediately back of the window as is usual in banks.

55 An opening 7, is provided between the end of the wall 4 and the end of the mirror 5,

through which opening the teller is visible and this opening also makes conversation as easy as with the present bank construction.

To prevent a thief from placing a revolver 60 around the end of the wall 4, and thus holding up the teller, I provide a plurality of vertical plates 8, spaced a suitable distance apart and extending between the walls 3, 4; these plates are so arranged that a revolver 65 cannot be pushed through them or the revolver cannot be held at an angle to shoot through the opening 7.

The transaction of receiving and paying 70 money is carried on in the following manner: A drawer 9, extends transversely across the window 2, and is set flush with the sill of the window and the drawer is covered by a slide 10, thus when the patron wishes to deposit money, the teller opens the slide 10, 75 the patron places the money in the drawer 9, the slide 10 is then closed and the drawer 9 withdrawn and the money removed therefrom by the teller standing back of the desk 6. If large bags of money are to be deposited 80 or withdrawn, they may be placed in a compartment 11, below the drawer 9, and which is opened by withdrawing the drawer 9 and slide plate 10.

In order that the watchman may look 85 through the window 2, and into the mirror 5, and see the safe or other equipment in the teller's compartment, I preferably place the safe 12, back of the teller which makes it 90 visible in the mirror. Other equipment such as files and the like can also be placed back of the teller so that the patron or watchman can readily see these as is usual in a bank.

A turret 13, is provided in the wall 1, to one side of the teller, and this turret is provided with port-holes 14, and peep holes 15, through which the teller can look and shoot when necessary to rout any bandits that may be in the bank. To protect the teller against any one entering his compartment through 100 a doorway, I provide a door 16, in the wall 1, the key to which is held by the teller and which can only be unlocked when the person comes to the window and receives the key. The door 16, opens into the vestibule 17, 105 which is closed by a door 18, opening into the teller's compartment and the door 18, can only be opened from the inside thus the teller is doubly protected by means of the doorways.

Having described my invention, I claim:

1. A burglar proof bank construction com-

prising a bullet proof wall, a window in said wall, an inclined mirror back of said window, the teller being adapted to stand to one side of said mirror thus being visible to one side of said mirror 5 therein to patrons standing in front of the window and a plurality of vertical plates extending across said window to prevent a bandit from placing a gun therebetween and covering the teller, a drawer extending transversely across the window and a plate covering the drawer, said drawer and plate being operable by the teller.

2. A burglar proof bank construction comprising a bullet proof wall, a window in said wall, bullet proof walls extending rearwardly from said window and on both sides thereof, an inclined mirror extending from one of said side walls and being spaced between the end of the mirror and the end 20 of the other wall through which the teller is visible, and a drawer extending transversely across the window and operable by the teller.

3. A burglar proof bank construction comprising a bullet proof wall, a window in said wall, bullet proof walls extending rearwardly from said window and on both sides thereof, an inclined mirror extending from one of said side walls and being spaced between the end of the mirror and the end of the other wall through which the teller is visible, and a drawer extending transversely across the window and operable by the teller, and a plurality of vertical plates spaced 35 apart and extending between said side walls.

4. A burglar proof bank construction comprising a bullet proof wall, a window in said wall, bullet proof walls extending rearwardly from said window and on both sides thereof, an inclined mirror extending from one of said side walls and being spaced between the end of the mirror and the end of

the other wall through which the teller is visible, and a drawer extending transversely across the window and operable by the teller, 45 and a plurality of vertical plates spaced apart and extending between said side walls, a turret in the front wall, said turret having post-holes therein, through which the teller can fire.

5. A burglar proof bank construction comprising a bullet proof wall, a window in said wall, bullet proof walls extending rearwardly from said window and on both sides thereof, an inclined mirror extending from 55 one of said side walls and being spaced between the end of the mirror and the end of the other wall through which the teller is visible, and a drawer extending transversely across the window and operable by 60 the teller, a door in said front wall, a vestibule back of said door, and a second door opening from the vestibule into the compartment back of said wall.

6. A burglar proof bank construction comprising a bullet proof wall, a window in said wall, bullet proof walls extending rearwardly from said window and on both sides thereof, an inclined mirror extending from one of said side walls and being spaced between the end of the mirror and the end of the other wall through which the teller is visible, and a drawer extending transversely across the window and operable by the teller, and a plurality of vertical plates spaced 70 apart and extending between said side walls, a turret in the front wall, said turret having port-holes therein, through which the teller can fire, a door in the front wall, a vestibule back of said door, and a second door opening from the vestibule into the compartment back of said wall.

In testimony whereof, I affix my signature.

DAVID G. EARL.
